Manuel Nieto
BY
S. O. Blackley
ATTORNEY

UNITED STATES PATENT OFFICE.

MANUEL NIETO, OF BROOKLYN, NEW YORK, ASSIGNOR OF ONE-FOURTH TO FRANCISCO LOPEZ, OF NEW YORK.

ELECTRIC HEATING AND SURFACE-FINISHING DEVICE.

Application filed February 25, 1928. Serial No. 256,835.

This invention relates generally to heating devices, and has more particular reference to a heating device for obtaining a smooth neat finish on plaster work in the initial stage of drying. More specifically stated the device is intended for use on the plaster of the walls and ceilings of rooms, though it is not limited to this use only.

The invention has for an object the provision of a device of the class mentioned, which is of simple durable construction, desirable and efficient in use, and which can be manufactured and sold at a reasonable cost.

15 The device has a substantially semi-cylindrical plaster engaging member with all lateral longitudinal elements of curved formation, and this member is of hollow construction of V-cross section. A winding backing member of U-cross section has a heating winding attached to its outer side, and is engaged within the hollow of the plaster member. A shell supports the plaster member and a stem connects with the shell. The leads 20 from the heating winding extend thru the stem, and connect with a rheostat attached at one end of the stem, and at the other end to a handle for manipulating the device. The plaster engaging member may be of various 25 lengths depending upon the size of a job the device is to be used on. The winding backing member may be adjustably mounted to be movable relative to the plaster member, as a means for changing the heat radiation from 30 the winding to the plaster member.

35 For further comprehension of the invention, and of the objects and advantages thereof, reference will be had to the following description and accompanying drawings, and 40 to the appended claims in which the various novel features of the invention are more particularly set forth.

45 Referring to the accompanying drawing, forming a material part of this construction:—

Fig. 1 is a front view of a device of the class mentioned.

Fig. 2 is a side view thereof.

50 Fig. 3 is a fragmentary vertical sectional view, taken on the line 3—3 of Fig. 1.

Fig. 4 is a fragmentary face view of the inner side of the plaster engaging member.

Fig. 5 is a fragmentary front view of the shell and stem of the device.

Fig. 6 is a fragmentary vertical sectional view, taken on the line 6—6 of Fig. 3.

Fig. 7 is a fragmentary front view of a modified form of the device.

Fig. 8 is a fragmentary view of a still further modified form of the device.

The reference numeral 10 indicates generally a semi-cylindrical plaster engaging member having its lateral longitudinal elements of curved formation, as for example indicated by numerals 11, and being of hollow construction, substantially V-shaped in cross section. A flange 12 extends completely around the back side of the plaster member, and the ends of the plaster member are formed with semi-circular lug recesses 13. This member 10 is made from insulating material, as hard rubber, or some fibrous composition.

A shell 14 engages over the flange 12 and has end lugs 15 engaging the recesses 13, while screws 16 engage the lugs 15 and the member 10 holding these parts together. A tubular stem 17 communicates with the interior of the shell. A winding backing member 18 of the same material as member 10, is of V-shaped cross section, and has a heating winding 19 attached to its outer side. This winding and member 18 engage within the hollow of the plaster member 10. One end of the winding 19 connects with a contact arm 20, and the other end with contact arm 21. These contact arms connect with conductor strips 23 supported to the shell 14, but insulated therefrom. A pair of leads 24 connect with the strips 23, and extend thru the stem 17 to a rheostat within the rheostat casting 25. The rheostat is operated by a control wheel 26. A tubular handle 27 is attached to the rheostat, and an electric cable 28 extends thru the handle to the rheostat.

Slide members 29 project from the rear side of the winding member 18, and slidably connect with guide members 30 projecting from the interior of the shell 14. Screws 31 rotatively mounted in the winding member 18, threadedly pass thru and engage the shell 14, and the projecting ends of the screws are provided with lock nuts 32.

In operation, the heating winding 19 is energized by current supplied thru cable 28, and controlled by rheostat wheel 26. Heat is transmitted to the plaster member 10. The device is then manually taken by the handle

27, and moved so that the plaster member 10 rubs up and down upon plaster in a state of drying. A very neat and smooth finish is thus put on the drying plaster. Supplementing the heat control of the device by means of the rheostat, are the adjusting screws 31. The lock nuts 32 may be loosened, and the screws turned to move the heating winding from the rear of the member 10, then the lock nuts reengaged.

10 Referring in particular to Fig. 7, a plaster engaging member 10' is illustrated, of exceptional length. In cases where very large surfaces are to be treated with the invention device, the long member 10' may be advantageously used.

Fig. 8 illustrates a plaster engaging member 10" so positioned that its length lies in the same direction as the length of stem 17. Certain persons may find this form more convenient than the first described form.

It is to be understood that not only plaster may be finished by means of this device but also other substances which may be used for substituting plaster such as a mixture of cement, lime and powdered marble. Where better grade work and appearance is desired, for instance in hospitals and dormitories, lime and pulverized marble may be mixed with gypsum and the work finished with my device which makes the wall waterproof, washable and allows original color to remain on the wall regardless of how frequently the wall is washed.

35 While I have shown and described a preferred embodiment of my invention, it is to be understood that I do not limit myself to the precise construction herein disclosed and the right is reserved to all changes and modifications coming within the scope of the invention as defined in the appended claims.

Having thus described my invention what I claim as new and desire to secure by United States Letters Patent is:—

45 1. A device of the class described, comprising a plaster engaging member of hollow construction, a winding backing member supporting a winding, engaged therein, a shell attached to the plaster engaging member, a stem connected with the shell, and handling means connected with the stem, the winding backing member being provided with projecting slide members engaging guide members

with projecting slide members engaging guide members projecting from the shell, and a means for adjusting the position of the winding member relative to the plaster engaging member.

2. A device of the class described, comprising a plaster engaging member of hollow construction, a winding backing member supporting a winding, engaged therein, a shell attached to the plaster engaging member, a stem connected with the shell, and handling means connected with the stem, the winding backing member being arranged for sliding within the shell, and screws rotatively connected with the winding backing member, and threadedly engaging the shell, as a means for adjusting the position of the winding relative to the plaster engaging member.

3. A device of the class described, comprising a plaster engaging member of hollow construction, a winding backing member supporting a winding, engaged therein, a shell attached to the plaster engaging member, a stem connected with the shell, and handling means connected with the stem, the winding backing member being provided with projecting slide members engaging guide members projecting from the shell, and screws rotatively connected with the winding backing member, and threadedly engaging the shell, as a means for adjusting the position of the winding member relative to the plaster engaging member.

4. A device of the class described, comprising a plaster engaging member of hollow construction, a winding backing member supporting a winding, engaged therein, a shell attached to the plaster engaging member, a stem connected with the shell, and handling means connected with the stem, the winding backing member being provided with projecting slide members engaging guide members projecting from the shell, and screws rotatively connected with the winding backing member, and threadedly engaging the shell, as a means for adjusting the position of the winding member relative to the plaster engaging member and lock nuts engaging the screws and abutting the shell.

50 In testimony whereof I have affixed my signature.

MANUEL NIETO.
